UNITED STATES PATENT OFFICE

ARMAND GODEFROID, OF BERLIN, GERMANY

CASH TILL WITH A COIN ASSORTER

Application filed November 17, 1931, Serial No. 575,622, and in Germany June 29, 1931.

My invention relates to a cash till with a coin assorter and it is an object of my invention to so design a cash till of this type that the coins are delivered to the assorter in two groups in succession, and not all together at a time. The function of the assorter is facilitated and rendered more reliable by this subdivision.

With the object of my invention in mind, I provide in a cash till having a coin assorter of any suitable kind, a coin receiver and a coin interceptor which are preferably operatively connected, and means for operating the receiver. The receiver delivers directly to the assorter those coins which possess the higher inertia, viz, larger and heavier coins which are sent flying past the interceptor and delivered directly to the assorter, and the interceptor receives and delivers to the assorter the smaller and lighter coins the inertia of which is not sufficient to carry them past the interceptor.

In the accompanying drawings several types of cash till embodying my invention are illustrated diagrammatically by way of example.

In the drawings:

Fig. 1 is a sectional elevation of a cash till having a rocking counter plate as the receiver,

Fig. 2 is a sectional elevation of a cash till having a conveyer as the receiver,

Fig. 3 is a sectional elevation of a cash till having a rocking counter plate and an intermittently fed conveyer for receiving the coins from the counter plate,

Fig. 4 is a sectional elevation of the upper portion of a cash till in which the intermittently fed conveyer receives the coins directly,

Figs. 5 and 6 are sectional elevations showing in two positions of its parts the upper portion of a cash till with a grid-shaped interceptor, and

Fig. 7 is a section on the line VII—VII in Fig. 5.

Referring now to the drawings, *a* is the casing of the cash till, *c* is a coin hole in its top plate, *n* is the assorter, and *o* is a collector below the assorter. *h* is an operating handle for the receiver, and *f* is its shaft.

Referring now particularly to Fig. 1, *b* is a rocking counter plate below the hole *c*, *d* is its pivot, *e* is a link pivoted to the free end of the counter plate *b*, and *g* is an arm on the shaft *f* to which the other end of the link *e* is connected. *l* is the interceptor, here shown as a concave or trough-shaped member, *m* is a pin about which it is pivoted, *k* is an arm on the interceptor, with a roller at its free end, and *i* is a cam on the shaft *f* which cooperates with the roller on arm *k*. *y* and *z* are checks limiting the stroke of the handle *h* through the cam *i*, and *x* is a spring on the pin *m* which holds the roller engaged with cam *i*. The spring may be dispensed with if the interceptor *l* is so designed or weighted that the roller at the arm *k* is held engaged with the cam *i* by gravity.

Fig. 1 shows the initial position of the parts. When an amount of money has been counted down on the counter plate *b* through the hole *c*, the handle *h* is turned in the direction of arrow *P*. The counter plate *b*, through link *e* and arm *g* on shaft *f*, is tilted into the position shown in dot-and-dash lines while at the same time the cam *i* moves the interceptor *l* into the position also shown in dot-and-dash lines in which its front edge is just below the rear edge of counter plate *b*. The heavier and larger coins which slide down on counter plate *b*, are shot past the rear edge of the interceptor *l*, and delivered directly to the assorter *n*. The smaller and lighter coins drop into the interceptor trough where they remain for the present. When the handle is returned to its initial position against the arrow *P* the interceptor and the counter plate return into the positions shown in full lines and the coins slide down from the interceptor *l* into the assorter *n*.

It will be understood that by the subdivision of the coins into two groups the load on the assorter *n* is relieved, its work is facilitated and its operation rendered more reliable.

The coins drop into the collector *o* which is equipped with the usual compartments and may be extracted like a drawer.

Referring now to Fig. 2, this cash till is designed substantially like the one just de-

scribed, but the counter plate *b* is replaced by a conveyer *p* on pulleys *q* and *r*. *s* is a ratchet wheel on the shaft of pulley *r*, with a holding pawl *w*, *u* is an arm on the shaft *f*, *t* is a toothed sector which is fulcrumed at the free end of the arm *u*, and *v* is a spring tending to hold the sector in mesh with the ratchet wheel *s*.

When the handle *h* is turned in the direction *P* the coins on the receiver or conveyer *p* which now moves to the right with its upper reach, are either thrown past the interceptor *l* or dropped on it, as described. When the handle *h* is returned to its initial position against *P*, the sector *t* moves past the teeth of the ratchet wheel *s* without moving them, and the wheel is held by its pawl *s* so that the conveyer remains stationary.

Referring to Fig. 3, the counter plate *b* is arranged as described but fulcrumed about at its centre, and adapted to deliver the coins to the conveyer *p* below its rear end. The conveyer *p* is equipped with transverse ribs 5 which are spaced apart so that the amount of each payment is received between two ribs. The handle *h* is shown depressed for tilting the counter plate *b* through mechanism which will be described, and the coins which slide from the counter plate are arrested by the rib 5*a*. When the rib 5*a* has moved through five pitches into the position 5*b* the coins are partly thrown past the rear edge of the interceptor *l*, and partly dropped into it, as described. 7 is a glass plate at the rear of an inspection opening in the top of casing *a* through which the coins on the conveyer are visible before being delivered.

10 is a lug on the handle *h* below its shaft *f*, and 11 is a double-armed lever which is engaged by the lug 10 at one end and with its other slotted end engages the interceptor *l*. Here, the interceptor *l* is tilted upwards when the handle *h* is depressed.

12 is a link, one end of which is pivoted to an extension of the handle *h* beyond its shaft *f* while its other end is pivoted to a lever 18, 16, 19 which is fulcrumed at 18. The link 12 is pivoted to arm 16. 14 is a link connecting the arm 13 to the counter plate *b*, and 15 is a pawl mounted to rock on the end of the third arm 19, with a spring 17 holding it engaged with the ratchet wheel *s* on the shaft of pulley *q*.

In its initial position the lever *h* is at the left of the position shown, and the counter plate *b* and the interceptor *l* are in the dotted positions. When the handle *h* is turned with the arrow *P* the coins drop from counter plate *b* and are delivered to the space between two ribs 5 on the conveyer *p* which is just below the rear end of plate 3. The handle *h* is now returned to its initial position against arrow *P* and at the next payment is depressed again, feeding the conveyer *p* through one pitch of ribs 5 as often as it is depressed. In the ex-

ample illustrated the money of a given payment arrives at the pulley *b* after six more payments have been made.

The cash till illustrated in Fig. 4 is similar to that in Fig. 2, the counter plate *b* being dispensed with in both cases. Details, however, are modified. 21 is a lever on the shaft of handle *h*, 33 is a link pivoted to the lever 21 at one end, 34 is a rocking lever fulcrumed at 28 to which the other end of link 33 is pivoted, 35 is a notched arm which is pivoted to the free end of lever 34, and 36 is a tooth on the arm which cooperates with pins 37 on the pulley *q*.

The interceptor is here designed as a star 27 with three arms forming between them seats for the coins delivered from the conveyer *p*, and three pins 31. 29 is an arm with a tooth 30 adapted to engage pins 31 at one end. Its other end is fulcrumed to handle *h* and 32 is a spring which tends to hold the tooth 30 engaged with pins 31.

When the handle *h* is turned in the direction of arrow *P* the tooth 36 feeds the conveyer *p* through one pitch of its ribs 5, and the coins at the pulley *r* are partly delivered to the assorter and partly to one of the seats between the arms of the star-interceptor 27. When the handle *h* is turned against arrow *P* the tooth 36 does not entrain the pins 37 but the tooth 30 engages one of the pins 31 on the star 27. In the present instance, each operation of tooth 36 turns the pulley *q* through 90 degrees and each operation of tooth 30 turns the star 27 through 120 degrees.

Referring now to Figs. 5 to 7, the conveyer *p* is provided as described, and fed by lever 21 on shaft *f*, and link 33 as described but the interceptor is stationary and cooperates with a wiper actuated by the handle *h*.

41 is the stationary interceptor which is curved on an arc of a circle about a pivot 55, slotted at 42 and equipped with a check bar 43 near its front end. 47 are a pair of arms which are fulcrumed about the (duplicated) pivot 55, 49 is a short arm on one of the arms 47, 50 is a link pivoted to its free end, 51 is a lever which is fulcrumed at 52 and connected to the other end of link 50, and 53 is a link which connects the lever 51 to an arm 54 on shaft *f*. 46 is a transverse bar at the upper end of arms 47, and 45 are teeth on the bar, each engaging in one of the slots 42. The teeth form a sort of rake by projecting into the slots of the grid 41.

Fig. 5 shows the initial position of the parts, and handle *h* is now depressed in the direction *P* when a payment has been made. The coins are partly thrown past the rear edge of the grid 41 and partly deposited on the grid where they are retained by the bar 43. Depression of the handle *h* causes the arms 47, with the teeth 45, to move in the direction *Q*, Fig. 5, past check bar 43 which is recessed for them, and past the coins on the

grid 41. The teeth now engage below the coins on the grid and when the handle *h* is returned to initial position they are wiped off the grid and dropped at its rear edge by the teeth 45.

5 It is understood that I am not limited to any one of the combinations of mechanisms shown and described. In particular, I may provide other means than the conveyer *p* for 10 inspecting the coins as they are moving toward the delivery end of the cash till.

I claim:

1. In a cash till, a coin assorter, a coin receiver adapted to deliver coins directly to said 15 assorter, means for operating said receiver, and an interceptor adapted to deliver to said assorter the coins not delivered directly.

2. In a cash till, a coin assorter, a coin receiver adapted to deliver coins directly to said 20 assorter, means for operating said receiver, and an interceptor operatively connected to said receiver and adapted to deliver to said assorter the coins not delivered directly.

3. In a cash till, a coin assorter, a rocking 25 counter plate adapted to deliver coins directly to said assorter, means for operating said plate, and an interceptor operatively connected to said plate and adapted to deliver to said assorter the coins not delivered directly.

30 4. In a cash till, a coin assorter, a rocking counter plate adapted to deliver coins directly to said assorter, means for operating said plate, and an interceptor adapted to deliver to said assorter the coins not delivered directly.

5. In a cash till, a coin assorter, a coin receiver adapted to deliver coins directly to said assorter, means for operating said receiver, and a concave interceptor adapted to deliver 45 to said assorter the coins not delivered directly.

6. In a cash till, a coin assorter, a coin receiver adapted to deliver coins directly to said assorter, means for operating said receiver, and a star-shaped rotary interceptor adapted to deliver to said assorter the coins not delivered directly.

50 7. In a cash till, a coin assorter, a rocking counter plate adapted to deliver coins directly to said assorter, means for operating said plate, and a rocking interceptor operatively connected to said plate and adapted to deliver to said assorter the coins not delivered directly.

8. In a cash till, a coin assorter, a rocking counter plate adapted to deliver coins directly to said assorter, a cam on said plate, means for operating said plate, and an interceptor adapted to be operated by said cam for delivering to said assorter the coins not delivered directly.

9. In a cash till, a coin assorter, an endless conveyer adapted to receive coins and to deliver them directly to said assorter, means for

feeding said conveyer, and an interceptor adapted to deliver to said assorter the coins not delivered directly.

10. In a cash till, a coin assorter, an endless conveyer adapted to receive coins and to deliver them directly to said assorter, spaced-apart coin-holding ribs on said conveyer, a casing having an opening for inspecting the coins on said conveyer, means for feeding said conveyer past said opening, and an interceptor adapted to deliver to said assorter the coins not delivered directly. 75

11. In a cash till, a coin assorter, a coin receiver adapted to deliver coins directly to said assorter, a star-shaped rotary interceptor adapted to deliver to said assorter the coins not delivered directly, means for operating said receiver, and uni-directional means operatively connected to said means for rotating said interceptor. 80

12. In a cash till, a coin assorter, a coin receiver adapted to deliver coins directly to said assorter, means for operating said receiver, an interceptor adapted to deliver to said assorter the coins not delivered directly, and means operatively connected to said operating means for wiping the coins from said interceptor. 85

13. In a cash till, a coin assorter, a coin receiver adapted to deliver coins directly to said assorter, means for operating said receiver, a cylindrical and slotted interceptor adapted to deliver to said assorter the coins not delivered directly, and a rake operatively connected to said operating means which is 90 mounted to rock about the axis of the cylindrical interceptor and to engage in said slotted interceptor for wiping the coins from it.

In testimony whereof I have signed my name to this specification.

ARMAND GODEFROID.
